ABSTRACT

Three-dimensional store in which the x- and/or the y-conductors with the z-conductors are connected in series to one or to two current sources. The internal dissipation of the store is thus reduced and a complete compensation both in waveform and in time of half the write current is obtained by the forbidding current.

A plurality of z-conductors may be used in each plane for reducing the impedance connected to the current source, said z-conductors forming mutual dummies.

THREE-DIMENSIONAL STORAGE DEVICE COMPRISING MAGNETIC MEMORY ELEMENTS

The invention relates to a three-dimensional storage device comprising magnetic memory elements coupled each with an x-, y- and z-conductor, to which x and y conductors selector switches are added for coupling the x- and y-conductors with a current source to supply half a write current, which has a value equal to half the current intensity required for writing information in the memory element.

Such storage devices may be employed inter alia in computers and telephone systems. In the known storage devices the x -, y - and z -conductors are connected to separate current sources. They have the disadvantage that due to the high number of current sources the overall internal dissipation is considerable so that the temperature may rise to high values, which requires special precautions for temperature-control.

The invention has for its object to provide a storage device of the type set forth, in which the internal dissipation is materially reduced as compared with the known three-dimensional storage devices.

The storage device embodying the invention is characterized in that the z-conductor of each memory element has added to it a switch for connecting in series upon selection of the memory element in accordance with the information to be recorded, the z-conductor of said memory element in opposite senses with one of the conductors of the group formed by the x- and y-conductors of said memory element for passing at a certain value of the information simultaneously with the write current, the write current counteracting inhibit or forbidding current through the z-conductor, having a value of half the write current.

In such a storage device no separate current sources are used for feeding current to the z -conductors so that the total number of required current sources is low.

An additional advantage of this storage device resides in that the forbidding current through the z -conductor coupled with a memory element is the same as the write current through the x - or y -conductor coupled with said memory element so that a complete compensation of the influence of the current through the x - or y -conductor on the memory element is always ensured.

Consequently, the control-device of the storage device embodying the invention is simpler than that of known storage devices, since the simultaneous appearance of the forbidding current and the half value of the write current is achieved without the need for taking special steps. Moreover, variations of the forbidding current due to temperature or voltage fluctuations compensate for the corresponding variations of the current through the x- or y-conductor.

Further advantages of the reduction of the number of current sources reside in that the number of setting members for adjusting the current values and the number of control-members readjusting the current strengths in dependence upon temperature and the number of buffers, formed, for example, by inductors employed for allowing the use of a lower supply voltage can be reduced accordingly.

The invention and its advantages will be described more fully with reference to the embodiments shown in the figures. Corresponding parts in the various Figures are designated by the same references.

FIGS. 1, 2 and 3 show three-dimensional storage devices embodying the invention.

FIG. 4, 5 and 6 show basic diagrams of stores embodying the invention comprising different transformer couplings between the current source and the conductors.

FIG. 7 shows a double balance-unbalance transformer coupling.

In known stores the memory elements are distributed in a plurality of planes. The memory elements of each plane are connected to a common z-conductor.

These z-conductors are each connected to an individual current source for passing a forbidding current through those planes in which the response of the memory elements to the write currents has to be forbidden. When the number of planes is high, the number of current sources is also high. These current sources have each a given internal dissipation which results in a high development of heat of all current sources, so that the temperature of the store as a whole is raised accordingly. FIG. 1 shows an embodiment of a three-dimensional storage device in accordance with the invention, which has a markedly lower rest dissipation

owing to the use of a single central current source. In this embodiment the store comprises memory elements arranged in p planes, each plane having 16 memory elements ($G_{11} \dots G_{44}$) formed by magnetic rings having a rectangular hysteresis loop, said elements being arranged in four rows and four columns. The rings of

each row are coupled with an x -conductor (x_1 to x_4) and the rings of each column are coupled with an y -conductor (y_1 to y_4). For the sake of clarity the drawing shows in each plane only one memory element G_{23} and the conductors x and y coupled with said element and

the conductors x_2 and y_3 coupled with said element and a z -conductor common in said plane ($z_1 \dots z_p$), extending parallel to the x -conductor. The x - and y -conductors in the various planes having the same indices are commoned. The commoned x - and y -conductors include

switches. The Figure shows the switch S_{x_2} included in the x_2 -conductor and the switch S_{y_3} included in the y_3 -conductor. The x -conductors are connected to each other at one end and at the other end they are connected to each other and via a conductor 1 to the

ected to each other and via a conductor T to the y -conductors connected to each other at their other ends. According to the invention the z -conductor of each memory element (z_1 to z_p) has added to it a switch (Sz_1 to Sz_p) in order to connect in accordance with the in-

formation to be written, the z-conductor of the memory element in series in opposite sense with at least one of the conductors of the group formed by the x- and y-conductors of said memory element, when this memory element is selected, by closing simultaneously a S_x and

element is selected, by closing simultaneously a S_x - and a S_y -switch. The series combination of the x - and/or y - and z -conductors is coupled with the current source I_1 for passing, at a given value of the information simultaneously with the write current, a forbidding current of half the write current counteracting the write current through the z -conductor.

The store furthermore comprises a network Dz added to each z -conductor and having the artificial impedance of said z -conductor. The network Dz , in its simplest form, may be formed by the series combination of a coil and a resistor. The switches $Sz_1 \dots Sz_p$ added to the individual z -conductors are formed by change-over switches, each of them connecting the z -conductor or the associated network in series with the

z-conductor or the associated network of any other plane. The read-write cycle is determined by the change-over switches Sw_1 and Sw_2 .

This storage device operates as follows: By way of example information is written in the memory element G_{23} . The switches Sw_1 and Sw_2 then are in the position shown. The switches $Sz_1, \dots, Sz_p$ occupy, as is shown, such a position that writing in the planes 1 and p is not forbidden. The current source I_x supplies half a write current, during writing in the memory element G_{23} , for which purpose the switches Sx_2 and Sy_3 have to be closed, the strength of said current being chosen so that it is half the strength required for changing over the magnetization to the direction determined by said current, via connecting terminal p , switch Sw_2 , switch Sx_2 , conductor x_2 in the planes 1 to p , conductor 1, switch Sy_3 , conductors y_3 in the planes p to 1, switch Sw_1 , switch Sz_1 , network Dz_1 , switch SZ_2 , conductor $z_2, \dots, Sz_p$, network Dz_p , each and via connecting terminal q back to the current source I_x . The memory element G_{23} in plane 1 is coupled with twice half the write current because the z-conductor does not convey current so that its direction of magnetization will match this current direction. The memory element G_{23} in plane 2 is coupled in total with half the write current because the z-conductor conveys a current opposite that through the x_2 - or y_3 -conductor. The memory element G_{23} in plane 2 will therefore not be able to adapt its direction of magnetization to the direction of half the write current. This method has the advantage that in the memory element G_{23} the variations in the current passing through the x_2 - or y_3 -conductor are completely compensated for by the variations in the current passing through the z_2 -conductor, since these currents are supplied from the same source.

In order to read the information the change-over switches Sw_1 and Sw_2 are changed over so that, when the current source I_x supplies a current pulse, this pulse passes via connecting terminal p , switch Sw_1 , the y_3 -conductors in the planes 1 to p , the switch Sy_3 , conductors x_3 in the planes p to 1, switch Sx_2 , switch Sw_2 , via earth to the connecting terminal q of the current source I_x . The current pulse thus passes through the x_2 - and y_3 -conductors in a direction opposite that during writing, whereas the z-conductor is not traversed by current. Thus all memory elements G_{23} are fully energized in the read direction and the memory elements whose direction of magnetization changes induce an output voltage in read conductors (not shown) provided for each plane.

The storage device described above has the advantage that only one current source is employed so that the internal dissipation is very low. Setting the current strengths only requires adjustment or readjustment of said current source. The currents passing through the x-, y- and z-conductors are identical so that the tolerance is improved. The current source may be provided with a buffer in order to allow the use of a lower supply voltage, the dissipation being thus further reduced.

The over-all impedance of the z-conductors is high in a store having a large number of memory elements. This means that in order to obtain a given steepness of the current pulses a high supply voltage is required, which involves high internal dissipation in the current source.

In the embodiment of a storage device shown in FIG. 2 in accordance with the invention this is obviated by using two current sources.

The store shown in this Figure comprises the same 5 number of planes, the structure is the same in each plane and the x- and y-conductors of the various planes having the same indices are interconnected in the same manner as those of the store shown in FIG. 1. Hereinafter only the differences will be set out. FIG. 2 shows only the planes 1 to 3 and the plane p , it being assumed that p is an even number. The store comprises two current sources I_{xz} and I_{yz} . The current source I_{xz} is connected by the connecting terminal p to contact 2 of a change-over switch Sw_{xz} and to contact 1 of a change-over switch Sw_{xz} , the switching arm of which is connected to one end of the parallel combination of the x-conductors having different indices of the series-connected x-conductors of the same indices, the other end being connected to the switching arm of the change-over switch Sw_{xz} . The contact 1 of the change-over switch Sw_{xz} is connected to one end of the series combination of the z-conductors or their networks Dz of the even-numbered planes, the other ends of which are connected to earth. The contact 2 of switch Sw_{xz} and the connecting terminal q of the current source I_{xz} are connected to earth. Likewise the current source I_{yz} is connected by the connecting terminal p to contact 2 of a change-over switch Sw_{yz} and to contact 1 of a change-over switch Sw_{yz} , the switching arm of which is connected to one end of the parallel combination of the y-conductors of different indices of the series-connected y-conductors of equal indices, the other end being connected to the switching arm of the change-over switch Sw_{yz} . The contact 1 of the change-over switch Sw_{yz} is connected to one end of the series combination of the z-conductors or their networks Dz of the odd-number planes, the other ends of which are connected to earth. The contact 2 of switch Sw_{yz} and the connecting terminal q of the current source I_{yz} are connected to earth. The switching arms of the change-over switches Sw are interconnected so that all switching arms are simultaneously in connection with contact 1 or contact 2 of the switches.

In order to write information the switches Sw have to be put in position 1. The current source I_{xz} then supplies a current equal to half the write current via switch Sw_{xz} in the position shown, switch Sx_2 in the closed position, the x_2 -conductors of the planes 1 to p , switch Sw_{xz} in the state shown, the z-conductor of plane p , the switch Sz_p in the state shown via the z-conductors or their networks Dz and the switches Sz of the even-numbered planes (not shown), the network Dz_1 , switch Sz_2 in the state shown and earth to the connecting terminal q of the current source I_{xz} . Likewise, the current source I_{yz} supplies a current equal to half the write current via switch Sw_{yz} in the state shown, switch Sy_3 in the state shown, the y_3 -conductors of the planes 1 to p , switch Sw_{yz} in the state shown and via the z-conductors or the networks Dz and the switches Sz of the odd-numbered planes (not shown), the z_3 -conductor, switch Sz_3 in the state shown, the network Dz_1 , switch Sz_1 in the state shown and via earth to the terminal q of the current source I_{yz} . In order to read the switches Sw are put in position 2 so that half the wire current passes via contact p of the current source I_{xz} , via switch Sw_{xz} in the state not shown, the x_2 -conductors in the planes p to 1,

switch Sx_2 in the closed state and switch Sw_x in the state not shown via earth to the terminal q of the current source I_{xz} . Likewise, half a write current will pass via contact p of current source I_{yz} via switch Sw_{yz} in the state not shown, the y_3 -conductors in the planes p to 1, switch Sy_3 in the closed state and switch Sw_y in the state not shown via earth to the terminal q of the current source I_{yz} .

It will be apparent from the Figure that only the series-connected z -conductors of the even-numbered planes are connected in series with the x -conductors and connected to the current source I_{xz} and that the series-connected z -conductors of the odd-numbered planes are connected in series with the y -conductors and to the current source I_{yz} . It is thus ensured that the impedance connected to the current sources amount to half those connected to the current source of FIG. 1, whilst the influence of half the write current through the x - or y -conductor connected to a memory element on said memory element is completely compensated for by a forbidding current passing through the z -conductor in accordance with the information, which conductor is coupled with said memory element. It is thus ensured that said additional advantages are maintained, whilst with regard to the known state of the art a considerable reduction of the number of current sources is achieved. Obviously the z -conductors may also be distributed in other groups, for example, the z -conductors of the planes 1 to $p/2$ and the z -conductors of the planes $(p/2+1)$ to p .

The embodiments shown in FIGS. 1 and 2 require a network Dz for each z -conductor. This requirement is obviated in the embodiment shown in FIG. 3. FIG. 3 shows a three-dimensional store, which does not require networks Dz . The configuration of this store comprising p planes having $n \times m$ cores is largely identical to that of FIG. 1. Hereinafter only differences will be explained. By way of example, each plane comprises 4 z -conductors, each coupled with a different group of $n \times m$ memory elements. In plane 1 these z -conductors are designated by z_{11} , z_{12} , z_{13} and z_{14} , in plane 2 by z_{21} , z_{22} , z_{23} and z_{24} , etc. To each plane are added three switches for selecting a z -conductor. For plane 1 these are the switches Sz_{11} , Sz_{12} and Sz_{13} , for plane 2 the switches Sz_{21} , Sz_{22} and Sz_{23} , etc. These switches are arranged so that one z -conductor of each plane can be connected in series with a z -conductor of any other plane. According as writing of information in a memory element of a plane has to be passed or has not to be passed, the z -conductor coupled with the memory element or a z -conductor not coupled with the memory element is selected with the aid of said switches.

The operation of this store will be explained with reference to examples, which are concerned with writing and reading of information in the memory elements Grq . In order to write the information the switches Sw_1 and Sw_2 have to be in the state shown and the switches Sx_r and Sy_q have to be closed. The states shown of the switches Sz correspond to information to be written. Thus a current circuit is completed via the connecting terminal p , the switches Sw_2 , the switch Sx_r , the conductors x_r in the planes 1 to p , the conductor 1, the conductor y_q in the planes p to 1, the switch Sw_1 , the switch Sz_{11} , the switch Sz_{12} , the conductor z_{12} , the

switch Sz_{13} , the switch Sz_{14} , the conductor z_{13} , etc. . . . the switch Sz_{p1} , the switch Sz_{p2} , the conductor z_{p2} , earth to the connecting terminal q . The current source I_r , connected to these terminals, conveys half a write current through said current circuit. The memory element Grq of plane 1 is not coupled with the z_{12} conductor through which the forbidding current is flowing. This memory element is therefore coupled with two half write currents passing through the conductors x_r and y_q . The direction of magnetization of this memory element will match the direction of the write current.

The memory element Grq of plane 2 is coupled not only with the half write currents through the x_r and y_q conductors but also with the forbidding current through the z_{23} conductor. The over-all current coupled with this memory element has the value of half the write current and is therefore not capable of adapting its direction of magnetization to the sense of the write current. In accordance with the states of the switches Sz in the other planes the same considerations apply to the memory elements Grq in said planes as to the memory elements Grq in the planes 1 and 2. To the memory element Grq of plane p for example, applies the same as to the memory element of plane 1, that is to say, that by passing the forbidding current through a z -conductor z_{p2} not coupled with the memory element this memory element will adapt its direction of magnetization to the sense of the write current.

Reading of information is performed in the same manner as described with reference to FIG. 1. The switches Sw_1 and Sw_2 have to be set in the other state than that shown.

An additional advantage of this store as compared with that shown in FIG. 2 is that each of the z -conductors is coupled with only one quarter of the number of memory elements in each plane, so that the impedance of these z -conductors in this embodiment is reduced to one quarter. It should be noted that a further reduction of the impedance of the z -conductors can be achieved by coupling each of the z -conductors with still fewer memory elements. For this purpose the number of z -conductors for each plane has to be increased accordingly. Moreover, as in the embodiment of FIG. 2 two current sources may be used. By these measures a lower supply voltage will suffice for obtaining current pulses having predetermined flank steepness. During the reading process the magnetization will decrease in these memory elements whose directions of magnetization are opposite those associated with the sense of half the write current during reading, which elements are not coupled with the forbidding current through the z -conductor during any preceding write periods of information in the other memory elements, since the hysteresis loop is not perfectly rectangular. As a result interference voltages are induced in the read wire, which interference voltages are termed "delta noise voltages."

In the store shown in FIG. 3 the currents through the x -, y - and z -conductors are identical and the current through the z -conductor is coupled with the memory elements in a sense opposite that of the current through the x - and y -conductors. The memory elements coupled with a current-conveying x -conductor as well as with a current conveying z -conductor or with a current-conveying y -conductor and a current-conveying z -con-

ductor will therefore not experience any change in the direction of magnetization. In the store shown in FIG. 3 a forbidding current is always conveyed through one quarter of all memory elements in one plane independently of the information so that in practice a lower "delta noise voltage" is obtained. A further reduction of the "delta noise" is found to be obtainable in practice by joining the z-conductors pairwise so that, when writing in a memory element coupled with one of the z-conductors of one pair a forbidding current is passed through this z-conductor or through the other z-conductor of the pair.

Wiring capacitances are present between the conductors located in the same planes and in the different planes. When the current source is switched on, they produce capacitive currents which adversely affect particularly the rising time of the current pulses through the conductors. Because the x-, y- and z-conductors are connected in series, the wiring capacitances will also give rise to current differences between the relative conductors, when the current source is switched on. FIGS. 4, 5 and 6 show a few embodiments of arrangements for the series connection of the x-, y- and z-conductors, in which the influence of stray capacitances is reduced.

FIG. 4 shows schematically the arrangement of the x-, y- and z-conductors, of a store of the kind shown in FIG. 3, which comprises, by way of example, 17 planes and having in each plane memory elements arranged in 64 rows and 64 columns. The circuitry of the z-conductors of plane 1 is shown in the Figure in a block V_{z_1} , from which two conductors emanate whose ends l_1 and l_2 may be considered to form the connecting terminals of the block V_{z_1} . Between the terminals l_1 and l_2 are connected in parallel the four z-conductors of plane 1: z_{11} , z_{12} , z_{13} and z_{14} , each of which includes a switch $S_{z_{11}}$, $S_{z_{12}}$, $S_{z_{13}}$ and $S_{z_{14}}$ respectively. If only one z-conductor is available in each plane, the relevant z-conductor, in this case that of plane 1, has connected to it the series combination of a network D_{z_1} having a switch S_{k_1} . The connecting terminals l_1 and l_2 of the block V_{z_1} are connected to the secondary winding of a transformer Tr_1 , the ends a_1 and a_2 of the primary winding being considered to form the connecting terminals of a block V_1 comprising the block V_{z_1} and the transformer Tr_1 . The circuitry of the z-conductors of the other planes 2 to 17 is represented in the Figure by the blocks V_2 to V_{17} , each of them being identical in structure to the block V_1 . The arrangement of the 64 x-conductors is shown in the Figure in a block K_x_1 , from which four conductors emanate, the ends d_1 , d_2 and f_1 , f_2 of which may be considered to form two pairs of connecting terminals of said block.

The connecting terminal d_1 is connected to 8 first connecting terminals of 8 switches S_1 and the connecting terminal d_2 is connected to 8 first connecting terminals of 8 switches S_2 . The Figures show only one switch S_1 and one switch S_2 . The total number of 8 switches S_1 and S_2 is indicated by arrows in the Figure. Between two connecting terminals of each pair of switches S_1 and S_2 is arranged the series combination of an x-conductor with an individually adjoined first diode D_1 , whose cathode is connected to the second connecting terminal of the switch S_2 . Of the 64 x-conductors with individual adjoined first diodes only the conductor

x_r and the diode D_1 , are shown. The terminal f_1 has connected to it eight first connecting terminals of eight switches S_4 and the terminal f_2 eight first connecting terminals of eight switches S_3 . The second connecting terminal of each switch S_3 is connected to the second connecting terminal of one of the switches S_1 . The second terminal of each switch S_4 is connected to the anodes of eight second diodes D_2 adjoined individually to x-conductors connected to different switches S_2 . The cathode of each these second diodes is connected to the anode of the relevant first diode. The Figure shows only one of the switches S_3 , switches S_4 and diodes D_2 .

The connecting terminals d_1 and d_2 of block K_x_1 are connected to the secondary winding of a transformer Tr_2 . The connecting terminals f_1 and f_2 of this block are connected to the secondary winding of a transformer Tr_3 . The ends b_1 and b_2 of the primary winding of the transformer Tr_2 and the ends c_1 and c_2 of the primary winding of transformer Tr_3 may be considered to form the connecting terminals of a block K_x including the block K_x_1 and the transformers Tr_2 and Tr_3 . The arrangement of the y-conductors is represented in the Figures by block K_y , which is constructed in the same manner as the block K_x . The connecting terminals a_1 and a_2 of the blocks V_1 to V_{17} and the connecting terminals b_1 and b_2 of the blocks K_x and K_y are all connected in series and via switch S_1 to the terminals p and q of the current source (not shown). The connecting terminals c_1 and c_2 of the blocks K_x and K_y are connected in series and via switch S_2 to the terminals p and q of the current source (not shown).

In order to write information the x- and y-conductors coupled with a group of memory elements have to be selected by closing one of the switches S_1 and of the switches S_2 both in the circuitry of block K_x and in that of the block K_y and in accordance with the information to be written one of the switches S_3 or the switch S_k has to be closed in each of the blocks V_1 to V_{17} . By closing the switch S_3 a current will pass via a connecting terminal p , switch S_3 , the primary winding of the transformers Tr_1 of the blocks V_1 to V_{17} , and the primary winding of transformers Tr_2 of the blocks K_x and K_y to the terminal q . This current induces currents of the strength of half the write current in the secondary windings of transformers Tr_1 and Tr_2 . Each of these currents will flow back via the connecting terminal l_2 and the closed switch S_2 or S_k via the z-conductor or the network D_z associated with said closed switch to the terminal l_1 . Half the write current through the secondary winding of the transformer Tr_2 of the blocks K_x or K_y will pass via the connecting terminal d_1 , the closed switch S_1 , and x- or an y-conductor respectively and the first diode D_1 included therein and the closed switch S_2 to the connecting terminal d_2 .

In order to read information from a group of memory elements, the x- and y-conductors coupled with said group of memory elements have to be selected by closing one of the switches S_3 and one of the switches S_4 both in the circuitry of the block K_x as in the circuitry of the block K_y . By closing the switch S_2 a current will pass via connecting terminal p , the switch S_2 , the network D_{st} , the primary windings of the transformers Tr_3 of the blocks K_x and K_y to the connecting terminal q . This current induces a current of the strength of half the write current in the secondary winding of trans-

former Tr_3 . This current will flow via the connecting terminal f_1 , the closed switch S_4 , the selected x - and y -conductors with any diode D_2 associated herewith, the closed switch S_3 to the connecting terminal f_2 of the transformer Tr_3 so that this current passes through the x - and y -conductors in a sense opposite that of the write current.

Since, the x , y and z -conductors are coupled via transformers with the supply circuit, the voltages of these conductors to earth can float and the stray capacitances of the current source are decoupled. Across each of the primary windings of the transformers Tr a voltage drop occurs and because they are connected in series, each winding has a different voltage to earth. These voltages are each operative across the series combination of the wiring capacitances between the primary and secondary windings of the relevant transformers Tr and indicated in the Figure at transformer Tr_1 by c_{p1} in block V_1 and the capacitances of the conductors to earth are indicated in the Figure for the various z -conductors of plane 1 by c_{p21} , c_{p22} , c_{p23} and c_{p24} in block V_{21} . The potential of each of the conductors in the various blocks will adjust itself to the voltage of this capacitive voltage divider so that between the blocks high voltage differences may occur, whilst via the mutual stray capacitances of the blocks capacitative currents may flow. By connecting the secondary side of the transformer Tr to earth, as is indicated in the Figure for the block V_{21} , no higher voltage differences can occur between the blocks than the voltages across the secondary windings of the transformers Tr . Thus the magnitude of the capacitative currents between the conductors is considerably reduced. Moreover, the earth-connection of the secondary sides of the transformers has the advantage that the switches S_2 , S_k , S_1 and S_2 are connected to earth on one side so that the switches may be formed by grounded-emitter transistors so that the response voltages of the bases of all transistors are the same. These transistors may be controlled by a simple control-device.

By connecting the secondary windings of transformers Tr to earth, the full voltages are operative across the capacitances c_{p1} between the primary and secondary windings of transformers Tr . These capacitances are then charged by currents passing via earth to the terminal q of the current source (not shown). This results in that the memory elements in the various planes are coupled with unequal currents during the rising time of the current pulses. FIG. 5 shows a variant of the circuit arrangement shown in FIG. 4, in which the currents passing via earth are drastically reduced by the use of balance-unbalance transformers.

FIG. 5 shows the identical blocks V_1 to V_{17} and the identical blocks Kx and Ky . The block V_{21} in block V_1 and the corresponding blocks not shown in the blocks V_2 to V_{17} are constructed as shown in FIG. 4. Also block Kx_1 in block Kx and the corresponding block not shown in block Ky are arranged as shown in FIG. 4. In the arrangement shown in FIG. 5 the terminals e_1 and e_2 of block V_{21} are connected to one side of the primary and secondary windings respectively of a transformer Tr_1' . The terminals a_1 and a_2 of block V_1 are connected to the other side of the primary and secondary windings respectively.

The terminals d_1 and d_2 of block Kx_1 are connected to one side of the primary and secondary windings respectively of transformer Tr_2' . The terminals d_1 and d_2 of block Kx are connected to the other side of the primary and secondary windings of said transformer. The terminals f_1 and f_2 of block Kx_1 are connected to one side of the primary and secondary windings of a transformer Tr_3' . The terminals c_1 and c_2 of block Kx are connected to the other side of the primary and secondary windings respectively of said transformer.

The terminals a_1 and a_2 of the blocks V_1 to V_{17} and the terminals b_1 and b_2 of the blocks Kx and Ky are all connected in series with each other and via switch S_5 to the terminals p and q of the current source (not shown). The terminals c_1 and c_2 of the blocks Kx and Ky are connected in series with each other and via switch S_6 to the connecting terminals p and q of the current source (not shown).

When writing information half the write current passes via connecting terminal a_1 of block V_1 , the primary winding of transformer Tr_1 and connecting terminal e_1 to the circuitry of the block V_{21} and via connecting terminal e_2 , the secondary winding of transformer Tr_1' , the connecting terminal a_2 of block V_1 to earth. Half the write current will traverse in the same manner the circuitries of the blocks V_2 to V_{17} . Half the write current passes furthermore via connecting terminal b_1 of block Kx , the primary winding of transformer Tr_2' , the connecting terminal d_1 of block Kx_1 , the circuitry of block Kx_1 , the connecting terminal d_2 of block Kx_1 , the secondary winding of transformer Tr_3' and the connecting terminal b_2 of block Kx and the circuitry of block Kx . Half the write current also passes the circuitry of block Ky in the same manner.

In reading the forbidding current will pass via connecting terminal c_1 of block Kx , the primary winding of transformer Tr_3' , connecting terminal f_1 of block Kx_1 , the circuitry of block Kx_1 , the connecting terminal f_2 of block Kx_1 , the secondary winding of transformer Tr_3' and the connecting terminal c_2 of block Kx , the circuitry of block Kx . Also the circuitry of block Ky is traversed in the same manner by the forbidding current.

The balance-unbalance transformers constitute an inductance for current differences between the primary and secondary windings.

The strength of the capacitative currents leading to current differences, when the current source is switched on, for example, the currents passing to earth via the earth capacitances of the z -conductors is reduced. The steepness of the current pulses through the conductors is thus affected to a lesser extent by the presence of the stray capacitances. The inductance of the balance-unbalance transformers can, however, not be raised arbitrarily. Therefore, in practice during switching on of the current source some amount of charging currents of stray capacitances will flow.

In order to obtain a short rising time of the current pulses, the current source, which is loaded, when switched on, by the impedances of the series-connected conductors apparently forming inductances, is constructed so that the voltage at the output terminals p and q is considerably higher during the starting time for overcoming the counter-voltages produced by said inductances than during the peak of the current pulse.

Thus high voltage, when the current source is switched on, leads to an increase in capacitative currents, which counteract the reduction of switching-on time aimed at in the arrangements shown in FIGS. 4 and 5. In order to obtain very short switching-on times it may be desirable to further reduce the influence of the stray capacitances. FIG. 6 shows a solution for this problem.

The arrangements of the z-conductors of plane 1 and of all x-conductors are shown in this Figure by the blocks V_i , k_x , the arrangements thereof being identical to the corresponding blocks of FIG. 4.

The connecting terminal a_1 of the circuitries of block V_1 is connected to one side of the primary winding of a transformer Tr_a and the connecting terminal a_2 is connected to one side of the secondary winding of said transformer Tr_a . The other ends k_1 and K_2 of the primary and secondary windings respectively of transformer Tr_a may be considered as the connecting terminals of a block A_1 including the block V_1 and transformer Tr_a . The arrangement of the z-conductors of planes 2 to 4 and of plane 17 is represented in the Figure by the blocks A_2 to A_4 and A_{17} , each being constructed like the block A_1 . The connecting terminals k_1 and k_2 of the blocks A_1 to A_4 are connected in series with each other and connected on one side to one side of the primary winding of a transformer Tr_a' and on the other side to one side of the secondary winding of said transformer. The other ends l_1 and l_2 of the transformer Tr_a' may be considered to form the connecting terminals of one of the blocks A_1 to A_4 and of the block B_1 including the transformer Tr_a' . The arrangements of the z-conductors of the planes 5 to 8, 9 to 12 and 13 to 16 are represented in the Figure by the blocks B_2 to B_4 , each being identical to block B_1 .

The connecting terminal b_1 of the circuitry of block K_x is connected to one side of a primary winding of transformer Tr_b and the connecting terminal b_2 is connected to one side of the secondary winding of said transformer. Likewise the connecting terminal c_1 of the circuitry of block K_x is connected to one side of the primary winding of transformer Tr_c and the connecting terminal c_2 is connected to one side of the secondary winding of said transformer. The other connecting terminals t_1 and t_2 of transformer Tr_b and the other connecting terminals o_1 and o_2 of the transformer Tr_c may be considered to form the connecting terminals of a block Rx including the block K_x and the transformers Tr_b and Tr_c . The arrangement of the y-conductors is represented in the Figure by a block Ry , which is identical to the block Rx . The terminals k_1 and k_2 of the block A_{17} and the terminal t_1 and t_2 of the blocks Rx and Ry are connected in series with each other, one end being connected to one end of the primary winding of a transformer Tr_b' and the other end to one end of the secondary winding of said transformer. The other ends of the windings of said transformers are connected in series with the connecting terminals l_1 and l_2 of the series-connected blocks B_1 to B_4 via a switch S_s , connected to the terminals p and q of a current source (not shown). The terminals o_1 and o_2 of the blocks Rx and Ry are connected in series with each other and connected at one end to one end of the primary winding of a transformer Tr_o' and by the other end to one end of the secondary winding of said transformer. The other ends of the windings of said transformer are connected

via switch S_L to the terminals p and q of the current source (not shown).

By this arrangement it is ensured that the currents of the wiring capacitances C_{p1} between the primary and secondary windings of the transformers Tr_1 of the blocks V and of the transformers Tr_2 and Tr_3 of the blocks K_x and K_y must flow via the balance-unbalance transformers Tr_a , Tr_b and Tr_c respectively, which form inductances for these currents. Moreover, the currents of four series-connected blocks, for example, A_1 to A_4 , are passed through the balance-unbalance transformer Tr_a' so that the difference current occurring in every four blocks has again to pass through an inductance. This also applies to the arrangements of the blocks B_2 to B_4 , which are identical to block B_1 . The currents through the series-connected circuitries of the block A_{17} and the currents of the blocks Rx and Ry passing through the connecting terminals t_1 and t_2 are passed through the balance-unbalance transformer Tr_b' . The currents of the blocks Rx and Ry passing through the terminals o_1 and o_2 are passed through the balance-unbalance transformer Tr_c' .

Thus, again an inductance for the difference currents passing through said transformers originating from not completely compensated capacitative currents is included for compensating for said currents.

By correct choice of all transformers it can be avoided that the wiring and earth capacitances of the conductors and of the transformers Tr_1 to Tr_3 are charged during the switching-on time to an extent exceeding the voltage associated with the peak of the current pulse so that the advantage is obtained that no high charging and discharging currents will appear.

The charging currents of the wiring capacitances between the primary and secondary windings of the balance-unbalance transformers — FIG. 6 showing only the wiring capacitances C_{p3} and C_{p4} of transformer Tr_a of block A_1 — do not produce a difference in current strengths neither through the primary and secondary windings of themselves nor through those of other balance-unbalance transformers connected to the former.

These capacitances are therefore rapidly charged and discharged and will be capable of following the voltage peaks occurring during the switching-on time. By replacing each balance-unbalance transformer in FIGS. 5 and 6 by the arrangement shown in FIG. 7, the charging currents of the stray capacitances between the windings of the balance-unbalance transformers are reduced and their charging time is prolonged. The arrangement shown in this Figure comprises two balance-unbalance transformers Tr_I and Tr_{II} connected in series that a current circuit is formed in the order: primary winding W_I of transformer Tr_I , primary winding W_I of transformer Tr_{II} , via a load B , secondary winding W_I of transformer Tr_I , secondary winding W_{II} of transformer Tr_{II} . It is thus ensured that the capacitative currents of the capacitances C_{p3}' and C_{p4}' of transformer Tr_I behave like a difference between currents through the primary and secondary windings of transformer Tr_{II} , whilst the capacitative currents of the wiring capacitances C_{p3}'' and C_{p4}'' of transformer Tr_{II} behave like a difference between currents through the primary and secondary windings of transformer Tr_I . This arrangement has the advantage that the capacitances

between the primary and secondary windings of the balance-unbalance transformers are charged via inductances.

What is claimed is:

1. A storage device comprising magnetic memory elements coupled each with an x , a y - and a z -conductor, the x - and y -conductors each including selection switches coupling said conductors to a write current source, said current source further supplying a counteracting current of half the strength required for writing information in said memory element, switching means responsive to the selection of a memory element associated therewith in accordance with the information to be recorded for connecting said z -conductor of each memory element in series in opposite senses with one of the conductors of the group formed by the x - and y -conductors of said memory element, and means for applying to said z -conductor simultaneously with the write current, said counteracting current of half the write current from said current source through said 2 -conductor.

2. A storage device as claimed in claim 1, wherein upon the selection of a memory element whose z -conductor must not carry a forbidding current during writing, said one conductor of the group formed by the x - and y -conductors of the memory element is connected in series with a network whose impedance is equal to that of the z -conductor.

3. A storage device as claimed in claim 2, wherein said storage device comprises a plurality of magnetic elements arranged in a plurality of planes, each of said planes made up of said memory elements arranged in a plurality of columns and rows, the memory elements being coupled to each column of each plane with said

x -conductor and in each row of each plane with said y -conductor, characterized in that in each plane said z -conductor is provided in common for a group of memory elements and in that for a network is coupled to each common 2 -conductor, said network having an impedance equal to that of the common z -conductor.

4. A storage device as claimed in claim 3 characterized in that in each plane a plurality of identical groups of memory elements are coupled each with a common z -conductor and in that said network is formed by a z -conductor coupled with a further group of memory elements.

5. A storage device as claimed in claim 4 characterized in that the x -, y -and z -conductors are coupled to their current sources through transformer couplings.

6. A storage device as claimed in claim 5 characterized in that the conductors are coupled via a first transformer coupling with one of a group of current circuits common to a plurality of conductors, said current circuits each being coupled with their current source via a second transformer.

7. A storage device as claimed in claim 5 characterized in that at least one of the transformer couplings comprises a balance-unbalance transformer.

8. A storage device as claimed in claim 7 characterized in that at least one of the transformer couplings comprises two balance-unbalance transformers connected so that a current supplied from the current source passes through the primary winding of one of the transformers, the primary winding of the other transformer, the secondary winding of one transformer and the secondary winding of the other transformer in that order.
